METHOD OF REENFORCING BEAMS

Charles G. Watson, Youngstown, Ohio

Application November 25, 1931, Serial No. 577,291

1 Claim. (Cl. 29—151)

In various types of building construction, it is often found that certain of the structural members are not of sufficient strength to withstand the stresses to which they are subjected or to which they may be subjected by loads greater than those for which they were originally designed.

In such cases, it becomes desirable to reenforce such structural members in situ, and for this purpose I have invented certain new and useful methods of reenforcing beams and the like, without resorting to the dismantling of the structures of which the beams are a part.

A primary object of the invention is to provide a novel reenforced beam for use as a structural member and a novel method of reenforcing such beams.

To the accomplishment of this and related ends, the invention, then, consists of the means hereinafter fully described and particularly pointed out in the claim, the annexed drawing and the following description setting forth in detail certain forms of construction embodying the invention, such disclosed means constituting, however, but a few of the various forms in which the principle of the invention may be used.

In said annexed drawing:

Fig. 1 is a cross-sectional view of a preferred form of the reenforced beam made in accordance with my invention; and Fig. 2 is a cross-sectional view of a modified form of reenforced beam made in accordance with the invention.

As will be seen from the drawing, each beam comprises an I-beam of usual cross-section, having a web 1, an upper flange 1a and a lower flange 1b, forming the base of the beam.

In the form illustrated in Fig. 1, the I-beam is reenforced by means of plates 2 which are bent into the form shown to provide portions 2a which

are in contact with the upper flange 1a of the beam, and portions 2b which extend to the outer edges of the lower flange 1b of the beam. Additional reenforcement for the I-beam may be provided by a plate or element 3 which is placed below the lower flange or base of the beam. With the various parts thus assembled, portions of the plates 2 and 3 are made integral with the flanges of the I-beam and with each other as by welding, as indicated in the drawing. It will be readily seen that the welding operations produce a rigid unitary beam having greater strength than the I-beam itself.

In the form of the invention illustrated in Fig. 2, the I-beam is reenforced by means of plates 4 which are bent intermediate their edges to form diverging portions 4a, which extend to the outer edges of the flanges of the beam. The edges of the plates are made integral with the flanges of the beam as by welding, and the plates are secured to the web of the beam as by spot-welding the plates thereto at longitudinally spaced points.

Other modes of applying the principle of my invention may be employed instead of the ones explained, change being made as regards the constructions herein disclosed, provided the means stated by the following claim or the equivalents of such stated means be employed.

I therefore particularly point out and distinctly claim as my invention:

The method of strengthening a bridge, or the like, supported on I beams to which access may be had, which comprises welding an edge of a steel plate integral with one edge of a lower flange on a supporting beam, forcing a section of said plate into contact with the web of said beam and welding the opposite edge of said plate integral with the upper flange of said beam.

CHARLES G. WATSON.
